Primary Examiner — Barbara Fox*Assistant Examiner* — Katie S Mroczka(74) *Attorney, Agent, or Firm* — Koppel, Patrick, Heybl & Philpott(57) **CLAIM**

The ornamental design for a chip, as shown and described.

DESCRIPTION

FIG. 1 is an isometric view of front, top, and right side of a new ornamental design for a chip;

FIG. 2 is a top view of the chip of FIG. 1;

FIG. 3 is a bottom view of the chip of FIG. 1;

FIG. 4 is a right side elevational view of the chip of FIG. 1; and,

FIG. 5 is a front elevational view of the chip of FIG. 1, the rear elevational view being a mirror image thereof.

1 Claim, 2 Drawing Sheets(56)
